METHOD OF DEFINING EXCAVATION LIMITS

Robert J. Hundhausen, Spokane, Wash., assignor of one-half to Daniel W. Butner, Spokane, Wash.

Application August 6, 1954, Serial No. 448,494

8 Claims. (Cl. 116—114)

My present invention is a means for fixing subterranean 15 location indicators.

An object of the invention lies in the provision of a method of marking subterranean locations to assist in maintaining limits of excavations.

It is conventional when building grades for highways and similar grade constructions to establish, by surveying practice, grade stakes or other reference points of elevation at distances remote from the area to be excavated in order to maintain a permanent reference elevation point from which the finished grade is determined by measurement employing the conventional surveyor's instrument and leveling rod. Obviously this requires considerable time as each reference point must be measured a relatively large number of times by the alternate cut and measure system until the desired grade is reached.

It is therefore another object of this invention to provide a method of marking prior to excavation a grade location at grade within the excavation area thus obviating the requirement of taking measurements at intervals during the course of the work to establish the desired grade.

Another object of the invention lies in the provision of a method of establishing limits of excavation to preclude excess excavation of material which necessitates resultant back filling operation.

Another object of the invention lies in the provision of a method of determining excavation limits wherein the vertical and angular plane surfaces of the finished excavation are initially located and defined and may be accurately controlled and maintained visually by the excavating machine operator.

In mining operations it is often found that ores which are economically profitable for mining are visually indistinguishable from ores which are not profitable. Therefore, under the present mining practice, it is conventional that samples of the mined ore be assayed to determine if the operation is producing profitable ores or not. This requires considerable time and also the nearly constant presence of a skilled engineer to direct the mining operation and determine which areas of ore should be mined and which should be left.

It is, therefore, a still further object of this invention to provide a method of fixing subterranean marks in an area within which an excavation is contemplated so that certain portions may be excavated when found economically profitable and other portions identified and left for subsequent excavation should conditions change to render the excavation of the marginal material profitable.

It is also customary to locate mining claims and other areas on the surface by means of stakes or other identifying appurtenances which may subsequently be destroyed by fire, vandals etc. and it is therefore included within the scope of this invention and a further object thereof to provide a method of marking areas permanently so they will not be liable to loss or removal by abnormal activities.

2

Another object of the invention lies in the provision of a method of fixing boundaries by disposing a substance distinguishable from the surrounding earth at one or more desired subterranean locations.

5 These and other objects of the invention will become apparent during the course of the following description.

In the accompanying drawings, forming a part of this specification, and in which like numerals are employed to designate like parts, I have illustrated practices employing the present method. It should be understood however that the drawings and description are illustrative only and are not intended to limit the invention except insofar as it is limited by the claims.

In the drawings,

Figure 1 is a vertical cross section taken through a portion of a hill upon which a proposed road bed and cut is disclosed in transverse cross section by dotted lines; and,

Figure 2 is a vertical cross section through a portion of earth including a body of ore to be mined.

In brief, the essence of the invention is to form one or more holes in the earth to a point at or beyond a limit of excavation and then to admit into the hole one or more materials, distinguishable from the surrounding earth and the other materials in such a way so as to provide means for the operator of an excavating machine to visually determine the progress of the excavation toward the limit and also to visually determine when the limit of excavation is reached.

30 In carrying out my invention, any means of forming a hole or of positioning a distinguishable material at a desired location is contemplated. The means which most readily come to mind include diamond drilling, rotary drilling, auger drilling, jet piercing, hammer percussion drilling, and drive pipe methods. It is not, however, necessary that the holes be round and therefore pits, cuts and trenches and similar openings may be employed if found desirable. These holes may be disposed on the vertical or inclined or even on the horizontal where found practical. The size and dimensions thereof are relatively unimportant since only the quantity of filling material is involved.

Referring now more particularly to the drawing, it will be seen in Figure 1 that I have disclosed by broken lines 45 a proposed roadway grade G which is disposed at a pitch or angle from the horizontal as is conventional on a highway curve and which is provided with a conventional recess draining ditch D at each side from which the upwardly angled walls W of the cut ascend.

Prior to excavating, the survey crew will determine the course and elevation as well as pitch of the desired finished grade and as this is determined, substantially vertical holes spaced transversely of the roadway are drilled as at 10, 11, and 12, preferably to a point below 50 the desired finished grade G. By measurement the holes are then filled with a distinguishable material 13 in the area defined by the bracket c to the finished grade G; then, as in the case of the holes 11 and 12, a segment of the hole immediately above the grade and of any desired length, preferably one or two feet, is filled with a second material 14 which is distinguishable from the surrounding earth and the first material 13. If desired, as indicated in hole 10, no filling is required above the grade G or, as indicated in hole 12, no filling above the segment b

55 or as an alternative a third distinguishable material 15 may be supplied to completely fill the upper segment a of the hole 11. Where the material 15 is exposed through the open mouth of the hole it provides a means of locating the course of the proposed roadway and also 60 provides the excavating machine operator with means for gauging the progress of the excavation.

So long as the material 15 is being removed while

excavating the operator is aware of the fact that the excavation is two feet (more or less) above the grade G. When the material 14 is found, the operator is aware of the fact that the excavating machine is approaching the grade G and when the material 14 ceases and the material 13 is found the excavation is complete to the grade G. As indicated in hole 10, the segments of the hole above the grade G may be left open in which case it is necessary for the operator to watch for the material 13 and when it is found the excavation is at grade. Obviously the segments *a*, *b*, and *c* may be of equal length and also there may be a greater number of segments above grade if desired and a plurality of materials distinguishable from the surrounding earth and each other may be employed (say to each one foot segment) and the depth of the excavation may then be accurately determined at any time by the material found in the hole during the operation.

It is obvious from this description that the pitch of the road may be controlled by measurement during the original surveying and drilling and subsequent surveying measurements will not be required since a fixed mark is disposed within the excavation area enabling the operator to accurately gauge the amount of earth to be removed from the excavation.

As in the case of the hole 16 which is drilled only to the grade or wall line, the material 14 is supplied in the lower portion or all of the hole 16 and when the excavator runs out of this material he knows the excavation is complete to the wall W or grade G.

The materials indicated by reference numerals 13, 14, and 15 are obviously isolated insofar as any grid or network is concerned and may be distinguishable by any known means, such as by color, texture, substance, electronics, magnetically, etc. Primarily the materials should be relatively inexpensive and for this reason it is contemplated employing natural or artificially colored materials such as rock, soils, organic compounds or manufactured materials. Of these limestone for white or varicolored material; various colored sandstones including red, green and other colors; shales, coals, magnetite sands, limonite or ochre soils, or if it is not convenient to secure these, crushed rocks of the immediate area as well as sand or other substances plentiful in the area may be employed. It is also contemplated using the cuttings removed from the hole during drilling by treating them with dyes or other additives or reagents to effect permanent color change or body substance. It is also contemplated to use a brittle or friable concrete or setting agent that will not be diffused in soil such as sand or flour dust and which may be easily removed by the excavating machine.

The invention further contemplates the use of radio active or magnetic materials to assist in locating holes provided for permanent reference points or for subsequent location where the flora or other action may disguise or cover a visual material, the latter being primarily of interest in locating survey corners, claim stakes and other reference points infrequently used and often difficult to locate. The filling materials may also be provided with a radio active tracer material to assist in location, or the lower filler material 13 may alone contain a radio active tracer material which will actuate a Geiger counter on the excavating machine to indicate when the grade depth is approached or reached.

The material may be introduced into the hole in any convenient manner, tamped to the proper grade level or elevation or it may flow freely where the grade construction may be within substantial limits.

In mining operations the use of the present method of defining excavation limits is obvious for open pit mining to define economically profitable ores for removal. However, it is also contemplated employing the method for tunnel or cave mining wherein the ore is caved from a body into hoppers from which the ore is discharged into

cars and removed from the mine. In this type mining it is required that the caving process not proceed upwardly to a point where the surface is disturbed since slides are then likely to occur. As indicated in Figure

5 2 of the drawing it is therefore effective to drill vertical or angular holes such as 17 from the surface S into the ore body O to a depth wherein the remaining earth is sufficient to support the surface against caving. The holes 17 are then filled with a material distinguishable 10 from the ore and surrounding earth so that as the ore is removed from within the earth and caved downwardly and the limit indicated by dotted line L is reached, the lower end of the hole 17 is opened and the distinguishable 15 material is found in the caved material and further upward removal of ore is terminated when so found. Under the present conventional method it is necessary for an engineer to continually measure and survey the caving process to determine where the point of danger is likely to occur and stop the mining operations at that point.

20 Many ore deposits are limited not by structural conditions but by what is known as "assay walls." These boundaries of a mineable deposit are determined by drilling and assaying. When a deposit has "assay walls" the boundaries of ore are limited by economic conditions determined by cost of mining and metal prices. Mining 25 conditions change from year to year causing boundaries to extend as metal prices increase or mining costs decrease. The grade of the ore, however, does not change. The holes drilled for assay purposes may be preserved as 30 a permanent field assay record by filling these holes with various colored materials and a record or log thereof maintained in the office. Thereafter in the future, mining can be extended into these marginal areas without additional engineering survey work in the field to re- 35 locate holes and determine assay limits by study or additional drilling and sampling. In this way, when the marginal ore becomes profitable to mine the mining may be extended into the ores defined by a distinguishable, say red, filler material previously located and should 40 mining costs permit, even later the mining may continue into even the lower grade ore which would be defined by a still further distinguishable material. Here again a trace of radio active material or magnetized material 45 near the mouth of the hole may be incorporated to assist in future location of the hole by Geiger counter or compass.

Having thus described my invention, I claim:

1. The method of defining excavation limits which consists in drilling a number of holes in the earth on planes defining selected ones of the excavation limits and to points beyond the excavation depth limit, depositing in the hole a material distinguishable from the surrounding earth in quantity to fill the hole to the excavation depth limit, and then depositing a second material distinguishable from the surrounding earth and the first named material for a portion of the balance of the hole, and then filling the balance of the hole with a third material distinguishable from the surrounding earth and the first and second named materials.

2. The method of defining excavation limits which consists in forming at least one hole in the earth to a point beyond the excavation limit, depositing in the hole a material distinguishable from the surrounding earth in quantity to fill the hole to the excavation limit, subsequently depositing a second material distinguishable from the surrounding earth and the first named material for a portion of the balance of the hole, and then filling the balance of the hole with a third material distinguishable from the surrounding earth and the first two named materials.

3. The method of defining excavation limits which consists in drilling a number of holes in the earth on the planes defining selected ones of the excavation limits and to points beyond the excavation depth limit, depositing 75 in the hole a substance distinguishable from the surround-

ing earth in quantity to fill the hole to the excavation depth limit, and then filling the balance of the hole with a second material distinguishable from the surrounding earth and the first named material.

4. The method of defining excavation limits which consists in forming at least one hole in the earth to a point beyond the excavation limit, depositing in the hole a material distinguishable from the surrounding earth in quantity to fill the hole to the excavation limit, and then depositing in the hole a second material distinguishable from the surrounding earth and the first named material.

5. The method of defining excavation limits which consists in forming at least one hole in the earth to a point substantially equal to the excavation limit, and then depositing in the hole an isolated material distinguishable from the surrounding earth.

6. In a method of marking a subterranean location the step which consists in disposing at a desired subterranean location an isolated friable substance distinguishable from the surrounding earth.

7. The method of defining excavation limits which con-

sists in drilling a number of holes in the earth to a point beyond the excavation limit, then filling the hole to the excavation limit with a material distinguishable from the surrounding earth, and then completely filling the hole in equal segments with a plurality of materials distinguishable from the surrounding earth and each other material.

8. The method of defining excavation limits which consists in forming at least one hole in the earth to a point beyond the excavation limit, and depositing in the hole an isolated material distinguishable from the surrounding earth in quantity to fill the hole to the excavation limit.
